INTERNAL COMBUSTION PUMPS

Fred F. Tessin, Santa Rosa, Calif.

Application September 27, 1957, Serial No. 686,636

6 Claims. (Cl. 103—75)

The present invention relates to improvements in internal combustion pumps and has particular reference to a pump in which the expansive force of an explosive gas is used directly to provide a pumping effect on a column of water or other liquid.

More particularly, it is proposed to utilize for this purpose a conventional reciprocating engine and to arrange a water column with respect to the piston so that the latter on its outstroke is made to advance the column of water toward a point of destination disposed at a higher elevation for discharge of a portion of said water at the free end of the column.

It is further proposed to provide an arrangement in which the back surge of the raised column of water is used to return the piston on its instroke to its starting position.

It is additionally proposed to provide for an intermediate step in which a new charge of water is introduced into the water column toward the end of the outstroke to compensate for the water discharged at the point of destination.

Again, it is contemplated to introduce the new charge under pressure and to cause the new charge to arrest the piston movement at a predetermined time and to initiate its return movement while the main column still advances toward the point of destination under the momentum imparted to the same by the piston originally, while the back surge of the column, after it has lost its momentum, is relied on to complete the return or intake stroke of the piston.

It is a further object of my invention to provide a cam shaft operated by the back and forth surges of the column of water and adapted for operating various accessories similar to parts conventionally operated by a cam shaft in a modern engine.

Further objects and advantages of my invention will appear as the specification progresses, and the new and useful features of the same will be fully defined in the claims hereto attached.

The preferred form of my invention is illustrated in the accompanying drawing forming part of this application, in which:

Figure 1 shows a vertical section through my pump, with the piston at the beginning of the outward stroke;

Figure 2, a similar section of a portion of the pump, with the piston nearing the end of the outward stroke; and

Figure 3, a section similar to that of Figure 2, with the piston at the end of the outward stroke.

While I have shown only the preferred form of my invention, it should be understood that various changes or modifications may be made within the scope of the claims attached hereto, without departing from the spirit of the invention.

My invention is here shown as applied to a two-cycle engine which has been selected for the purpose of the present description as being the preferred form and as

being the best adapted for the purposes of the present invention.

Referring to the drawing in detail, my invention comprises, in its principal features, a cylinder 1, of suitable length having a cap 2 at its upper end and an elbow 3 at its lower end, a pressure accumulator 4 surrounding an intermediate portion of the cylinder, and a piston 5 reciprocable in the cylinder.

Fuel is injected into the cylinder in any suitable manner employed in two-cycle engines through the hole 6.

The elbow 3 is connected, in any suitable manner, to piping 7 including a vertical element 8 leading to a point of destination, such as a tank 9 disposed above the level of the pump, into which the water is to be pumped.

15 The cylinder is formed, immediately above the pressure accumulator, with an exhaust port 10 and an air intake port 11 to which air is admitted under pressure.

The pressure accumulator is in the nature of an annular chamber surrounding an intermediate section of the cylinder and communicating with the latter through a series of ports 12 at the bottom end of the chamber.

20 The chamber communicates with a source of water supply through a conduit 13. The water is fed into the chamber under pressure in any suitable manner and provides for a pressure cushion above the water, as at 14.

The piston 5 is in the form of an annular skirt 15 having a close sliding fit in the main cylinder and has a dome-shaped head 16 to correspond to the shape of the dome-shaped cap of the cylinder.

25 30 The full length of the piston is such that when the piston is in its uppermost position, as shown in Figure 1, with its upper end slightly spaced from the cap of the cylinder to form a combustion chamber indicated at 17, the bottom end of the apron extends slightly below the lower end of the pressure accumulator 4 and closes the ports 12 as well as the ports 10 and 11.

The skirt is preferably made in two vertically aligned sections 15a and 15b connected by central vanes 18 in such a manner as to leave an opening 19 of considerable length between the two sections. This opening, in the position shown in Figure 1, that is, at the beginning of the outward stroke, does not communicate with any of the ports 10, 11 and 12, but is intended for cooperation with the ports 12 at a later stage.

40 45 The piston is hollow, of substantially uniform cross-section, except for reinforcing ribs, and has a capacity only slightly less than that of the cylinder.

As the piston moves downward into the position shown in Figure 2, its upper end clears the ports 10 and 11, and the lower end of the opening 19 enters into registry with the ports 12 in the cylinder.

As it advances still further into the position of Figure 3, the port situation remains substantially the same.

50 55 In operation, let it be assumed that the piston is at the beginning of its outstroke. At this time, the piston, the lower end of the cylinder, the elbow 3 and the piping 7—8 are filled with a solid body of water, and the pressure accumulator is filled to the height indicated and under pressure.

60 65 As the gas in the chamber 17 explodes, the piston is forced downward on its outstroke and pushes the entire body of water contained in the cylinder and the piping to cause the water to rise in the pipe and a portion to overflow into the tank at the upper end of the pipe.

As the upper end of the piston passes the ports 10 and 11, the gas in the combustion chamber will escape through one of said ports, while fresh air rushes into the other port.

70 75 At the same time, the opening 19 in the piston is made to register with the ports 12 and water under

pressure is made to rush into the piston from the pressure accumulator 4.

This new charge of water, while not interfering with the momentum of the water below the port 12, adds to the body and arrests the downward motion of the piston in such a manner that the latter comes to a stop very quickly, as shown in Figure 3, which indicates the end of the out movement of the piston.

Since, even in the position of Figure 3, the water keeps charging from the pressure accumulator, it initiates return movement of the piston until the opening 19 rises above the ports 12.

At this time the column of water in the piping 7-8 has lost its momentum and surges back and drives the piston back to its initial position, so as to compress the air admitted through port 11 for a new cycle of operation.

It will be noted that thus, for each power stroke of the piston, a certain amount of water is discharged through the open end of the pipe 8, and a similar amount is added to the column from the pressure accumulator, the two amounts necessarily corresponding, because the pressure accumulator maintains the column of water solid, and adds an amount of water equal to that discharged in each cycle.

It should also be noted that the piston is free-floating and does not need any positive stop to limit its out-stroke, the water from the pressure accumulator taking care of the arresting of the piston somewhat before its momentum has expired, and initiating the return movement of the piston while at the same time filling the space left by the retreating piston and thus adding a new charge to the system.

As an added feature, I provide means actuated by the surges of the water column in opposite directions for operating various control elements and accessories, such as the fuel injector, fuel pump, and possibly a pump for feeding the pressure accumulator.

This means comprises an hydraulic motor including a cam shaft 20 having a fly wheel 21 and a crank 22, with a piston rod 23 connecting the end of crank to a piston 24. The latter is mounted for reciprocating motion in a cylinder 25, one end of which is connected to the side of cylinder 1, at the lower portion of the latter, by means of an elbow 26.

This piston is thus operated in an upward direction by the momentum of the water column on the power stroke and in the opposite direction by the momentum of the fly wheel, when the pressure in the water column drops.

It will be noted that the bottom of the main piston 5 never reaches the water inlet of the elbow 26, so that it does not interfere with the operation of the hydraulic motor. The latter must be of such displacement that enough power for the work of the motor will be derived, and its fly wheel must be massive enough so that the rotation will be smooth in character.

Since the pump described hereinabove has no suction, the water to be pumped must be forced into the water column. The pressure accumulator must be sufficiently large to contain the water to enter in each cycle, together with the air for its operation.

The amount of water entering in each cycle depends of course on the pressure against which the pump is operating, and may be several times the volume of the combustion space. Water may be forced into the accumulator by a secondary pump, say a centrifugal pump, or by any other means, as for instance, by gravity.

It is only necessary that the water in the accumulator be under sufficient pressure that injection into the main body of the water will be complete at the end of the charging period.

My improved pump operates in a two stroke cycle, a compression and an expansion stroke corresponding to the instroke and outstroke of the water column. The cycle

of the operation commences with the closing of the ports 10, 11 and 12 at the beginning of the instroke and compression of the combustion space.

Then the fuel pump operates at the beginning of the outstroke and energy derived from combustion accelerates the water column so that when the ports 10, 11 and 12 again open the water column still continues in outward movement until its energy is exhausted. Although the two strokes are of equal duration, the outstroke of the water column is longer, the difference this represents in volume of water being the output of the pump.

It is during the latter part of the outstroke that the combustion space is scavenged and as much water as leaves the water column at its outer end is restored to it through the ports 12. When these ports open pressure in the accumulator establishes flow into the space under the piston head, stopping the piston from following the water column and reversing its motion so that at the end of the outstroke it is again on the point of closing the ports 12.

Thus, at the beginning of each cycle the water column is filled to the same point as is necessary for the stability of operation of the pump.

In order that the upper part of the piston skirt will not descend far enough to cut off the inlet flow through ports 12 before the piston can be halted, the inlet area must be made wide. This may be accomplished as shown, by making the gap in the piston skirt as wide as need be, and locating the stationary ports 12 in the cylinder wall to match perfectly.

The pump is to be started by first bringing the water column into motion. This may be accomplished by applying compressed air to the combustion space, in about the same manner as in starting internal combustion engines.

The air for the intake ports 11 is controlled by the fuel pump shaft 20, and on turning this shaft by an outside means at a speed the same as the cyclic speed of the pump, surging of the water column will commence and take control of the fuel pump motor, whereupon regular operation of the pump may begin.

In case the heat of combustion should develop a tendency to vaporize a portion of the water in the upper end of the piston, it may be desirable to create a certain amount of circulation in the piston, which may be easily accomplished by diversifying the angularization of the ports 12 in the cylinder, some discharging in an upward direction, and others discharging horizontally or in a downward direction, as shown.

I claim:

1. In an internal combustion pump of the character described, a cylinder, a piston reciprocable therein and having a head forming a combustion chamber with the cylinder and a skirt depending from the head, piping connected to the cylinder and shaped for supporting a column of water with one end bearing against the piston head and the other end presented at a higher elevation whereby a portion of the column is discharged at said higher elevation when the piston head is forced outward by an explosive charge in the combustion chamber, and means mounted upon the cylinder for injecting a charge of water under pressure through the piston skirt into the column when the piston has reached a predetermined position, whereby the piston movement is arrested and reversed while the outward movement of the column below the point of injection is continued temporarily.

2. In an internal combustion pump of the character described, a cylinder, a piston reciprocable therein and having a head forming a combustion chamber with the cylinder and a skirt depending from the head, piping connected to the cylinder and shaped for supporting a column of water with one end bearing against the piston head and the other end presented at a higher elevation whereby a portion of the column is discharged at said higher elevation when the piston head is forced outward

by an explosive charge in the combustion chamber, and means mounted upon the cylinder for injecting a charge of water under pressure through the piston skirt into the column when the piston has reached a predetermined position, whereby the piston movement is arrested and reversed while the outward movement of the column below the point of injection is continued temporarily, the column of water being operative, after losing its momentum, to return the piston to its starting position.

3. In an internal combustion pump of the character described, a cylinder, a piston reciprocable therein and having a head forming a combustion chamber with the cylinder and a skirt depending from the head, piping connected to the cylinder and shaped for supporting a column of water with one end bearing against the piston head and the other end presented at a higher elevation whereby a portion of the column is discharged at said higher elevation when the piston head is forced outward by an explosive charge in the combustion chamber, and means mounted upon the cylinder for injecting a charge of water under pressure through the piston skirt into the column when the piston has reached a predetermined position, whereby the piston movement is arrested and reversed while the outward movement of the column below the point of injection is continued temporarily, the column of water being operative, after losing its momentum, to return the piston to its starting position, and the cylinder having exhaust and intake ports normally closed by the piston and located to be opened by the piston during the injection period.

4. In an internal combustion pump of the character described, a cylinder, a piston reciprocable therein and having a head forming a combustion chamber with the cylinder and a skirt depending from the head, piping connected to the cylinder and shaped for supporting a column of water with one end bearing against the piston head and the other end presented at a higher elevation whereby a portion of the column is discharged at said higher elevation when the piston head is forced outward by an explosive charge in the combustion chamber, and means mounted upon the cylinder for injecting a charge of water under pressure through the piston skirt into

the column when the piston has reached a predetermined position, whereby the piston movement is arrested and reversed while the outward movement of the column below the point of injection is continued temporarily, the injecting means comprising a pressure accumulator surrounding the cylinder intermediate the length thereof, means for forcing water thereinto under pressure so as to leave an air cushion above the water and cooperative ports in the cylinder wall and the piston skirt positioned for registry when the piston reaches said predetermined position.

5. In an internal combustion pump of the character described, a cylinder having a cap at the upper end thereof with fuel injecting means in the cap, the cylinder having 15 exhaust and intake ports spaced from said cap, a pressure accumulator mounted around the cylinder below said ports and having delivery ports communicating with the inside of the cylinder, a piston slidable in the cylinder and having a head cooperating with the cylinder cap in forming a combustion chamber and having a skirt extending into the cylinder, the piston skirt being made to cover the exhaust and intake and delivery ports when the piston is in its uppermost position and having an opening in the side wall thereof intermediate its length, the exhaust and intake ports being located for uncovering by the piston on its outward stroke under the influence of a charge exploded in the combustion chamber, and the piston skirt opening and the delivery ports being located for registry simultaneously with the opening of the exhaust and intake ports.

6. An internal combustion pump as defined in claim 5, in which the accumulator has means for forcing the water into the piston through the registering piston skirt opening and the delivery ports to arrest further advance of the piston and to initiate return movement of the piston.
